ELECTRICAL SWITCH GEAR

Allen M. Rossman, Wilmette, Ill., assignor to
 Rossman Engineering Company, Chicago, Ill.,
 a corporation of Illinois

Application February 5, 1934, Serial No. 709,761

18 Claims. (Cl. 175—298)

This invention relates in its broad aspects to electrical switchgear applicable to power stations, substations, and switching stations, and is particularly concerned with novel and improved arrangements for switching units of the type in which the circuit breaker is portable and easily removable from the remainder of the structure.

The leading aims underlying the invention are to simplify both the method of and the means for moving the circuit breaker into and out of its operating position in the housing structure and the method of and means for connecting the circuit breaker to and disconnecting it from the portions of the electrical circuits which are stationary in the housing structure.

In prior designs of switchgear having easily removable oil circuit breakers, three methods are used for connecting the circuit breaker to the stationary structure.

In the first method the circuit breaker is mounted on a pair of horizontal rails. The movable circuit contacts, which are a rigid part of the circuit breaker assembly, are lined up very accurately with the stationary contacts and the circuit breaker is pushed horizontally into its normal operating position by means of a gear and rack or some other equivalent device, dependence being placed on accuracy of alignment to insure proper contacting of the current carrying parts.

In the second method, the circuit breaker is pushed horizontally into the stationary housing and is then elevated to its operating position by means of a screw device or some other equivalent mechanism. With this method of handling, the rigid upward extending contacts on the circuit breaker must be lined up accurately with the stationary contacts and suitable guiding devices must be provided to insure that the current carrying parts register properly.

In the third method, the circuit breaker is pushed horizontally into the stationary housing whereby the rear terminals of the circuit breaker are moved into register with their corresponding stationary terminals by the movement of the circuit breaker into its operating position, while the connections to the front terminals of the circuit breaker are made subsequently by closing disconnecting switches.

All three methods have the objection that they require a high degree of accuracy in design, fabrication, and assembly to insure a proper registration of contacting parts. Misalignment will cause trouble which can range from overheating of contacts to damaged parts due to the jamming of the heavy circuit breaker against the comparatively light circuit terminals.

Method three has the further objection that it leaves live parts exposed, accidental contact with

which can cause damage, injury, or even fatalities.

One object of my invention is to separate the double function of pushing the circuit breaker into its operating position and closing the circuit contacts, into two independent, non-simultaneous functions.

A second object is to eliminate the necessity for close alignment of the circuit breaker in the structure which has heretofore been necessary to insure accurate registration of the circuit contacts.

A third object is to insure that all high voltage parts are adequately insulated while the circuit breaker is in service.

A fourth object is to provide interlocking means to prevent accidental arcing at the circuit disconnecting contacts.

A fifth object relates to providing a new design of switching unit which is lighter, simpler, and less expensive than has heretofore been available.

Other objects will be apparent from the disclosure.

I will now describe methods of constructing a switching unit embodying the principles of the present invention, reference being made to the following drawings:

Figure 1 is a sectional elevation of a switching unit taken along the line 1—1 in Figure 2.

Figure 2 is a sectional plan of the switching unit assembled in a row of units taken along the line 2—2 in Figure 1.

Figure 3 is a front elevation showing the arrangement of contact arms.

Figure 4 is a detail in partial section of one of the contact arms shown in front elevation.

Figure 5 is a detail of another type of contact arm, shown in side elevation.

Figure 6 is a sectional elevation of a switching unit designed with a double bus.

Figure 7 is a detail of a stick for operating the movable contacts.

Figure 8 is a sectional elevation of a switching unit similar to Figure 1 but having a different form of bus and bus housing.

Figure 9 is a plan of a row of units of the type shown in Figure 8.

Figure 10 is a detail of an alternate type of movable contact member in engagement with its co-operating stationary contact member, the latter shown in section.

Figure 11 is a front elevation of the contact members of Figure 10.

Figure 12 is a detail partly in section of the contact member of Figure 5 shown in co-operation with its respective stationary contact.

In Figure 1 is shown a sectional elevation taken along line 1—1 of Figure 2 of a switching unit embodying the principles of the present invention. In general, the switching unit is of the class de-

scribed in my earlier disclosures, Patent No. 1,830,409, dated November 3, 1931, and application Serial No. 440,606, filed March 31, 1930. In common with these disclosures, the present invention consists of a vertically disposed fabricated metal enclosing structure, comprising a structural framework A, supporting sheet metal walls B, thus forming several compartments, one compartment 2 housing a circuit breaker 1 bus bars 3 disposed within a separate compartment 4 above the circuit breaker, and a third compartment 6 in which terminates a feeder cable 5. The switching unit is designed to be placed in line with a number of similar units in such a manner that the bus bars 3 extend continuously through the line of switching units, the bus bar compartments 4, which fit together to form one continuous tubular housing, in the manner disclosed in the above mentioned documents.

Unlike the earlier disclosures, however, the circuit breaker 1 is not raised into the operating position, but is merely rolled into place within the enclosure by means of a small individual truck 7 mounted on wheels 8. Instead of an individual truck, the breaker can be moved into the compartment by means of an industrial type truck and set down on the floor, after which the truck can be removed. In either case, the breaker 1 rests on the floor, thereby relieving the frame structure A of the duty of supporting its weight. The necessity of extreme accuracy in guiding the breaker into operating position is also obviated in the present design by provisions which will be described later. These features of lightness of structure and the elimination of the necessity for accurate guides, etc., result in a simpler, lighter, and less expensive switching unit.

A switching station of this type is made up by assembling a group of switching units, setting them in alignment, and connecting their respective bus sections 3 in series to form a continuous bus. One set of circuit breaker terminals in each switching unit are adapted for connection with the bus conductors 3 while the opposite terminals 45 are adapted to connect to an external circuit which feeds power to or is fed from the bus bars. The external circuit terminates in the terminal chamber 6 in the form of cables 5.

Connection is made between the front row of terminals 15 on the circuit breaker and the bus bars, after the circuit breaker has been set in operating position by means of hinged disconnect arms 9, each of which is provided with a contact head 11. The latter member is adapted for co-operating with stationary contact member 13, comprising a connector which will be described later disposed within a hollow insulating bushing which is fixed to the frame structure. The bus bars are connected respectively by means of conductors 16 to the terminals 101 on the rear end 60 of the stationary contact members 13. The terminals are connected conductively to the connectors within the hollow insulating bushings.

A plan of the contact members showing their relative positions within the structure is shown in Figure 2 which is a section taken along a line 2-2 in Figure 1. This drawing also illustrates the position of the switching unit relative to the other units in line, the circuit breaker compartment 2 being shown between two adjacent compartments 2A, 2B.

Figure 3 is a front elevation of the circuit breaker 1, disconnect arms 9, and stationary contact bushings 13. Although a three-phase unit is illustrated, as evidenced by the three circuit

breaker terminals in line and corresponding arms, contact members, and bus bars, circuits of other numbers of phases can be designed for by applying the same principles of construction.

The stationary members 13 are mounted on a panel 34 and extend through apertures in the panel into the bus bar compartment 4. This panel is supported on the structural frame of the unit and forms part of a partition between the circuit breaker compartment 2 and the lower 10 extension of the bus bar compartment 4.

The rear row of circuit breaker terminals 20 is connected with the cables 5 by a row of disconnect arms 10 similar to those 9 in the front row but shorter. A contact head 12 on the end 15 of each arm co-operates with a stationary contact member 14.

The three lower stationary contact members 14 are mounted in alignment on a panel 35 which is supported on the framework A and 20 forms part of a partition 23 between the circuit breaker compartment and the cable terminal compartment 6. Each stationary contact member 14 extends through an aperture in the panel 35 into the terminal compartment 6. A current transformer 24 is connected to each terminal 101 on the rear end of each of the contact members 14. The incoming cables 5 are connected to the other terminals of the current transformers so that one transformer is connected in 30 series between each cable and its corresponding stationary contact member 14. In some installations current transformers are connected in only one or two of the phases.

The cables enter the terminal chamber 6 35 through a conduit 25 at the bottom of the chamber. If it is more convenient for the cables to enter from above, the compartment 6 can be located as shown in broken lines 6', in which case the current transformer 24 would be mounted 40 above the contact bushing 14.

The use of the current transformers for operating meters and overload relays, etc. is well known.

The contact bushings 13, 14 can be spaced 45 farther apart horizontally than the circuit breaker terminals 15 to provide greater clearances as shown in Figure 3. The two outer disconnect arms of each row are bent outward so that the connectors 11 register with the hollow 50 bushing 13.

The disconnect arm 9 consists of a rigid insulated conductor connected by hinged joints to the contact head 11 at the top and to the circuit breaker terminal 15 at the lower end. 55

The joints in the arm are protected against accidental contact by means of insulating sleeves 18, 19.

Each of the short disconnect arms 10 is connected in a similar manner to one of the circuit breaker terminals 20 in the rear row by means of a flexible joint which is insulated by a sleeve 21. The upper joint between the arm 10 and connector head 12 is also insulated by a sleeve 22.

Referring now to Figures 4 and 5, which show 65 the front and side elevations of embodiments of the jointed disconnect arm, the rigid conductor 9 is connected to the head 11 by means of a hinged joint 26. This joint consists of a lug 27 on the head member 11 disposed between two 70 ears 28, 29 on the arm 9 and a bolt 30 inserted through registering holes in the lug and ears. Clearances in the lug 27 around the bolt 30 and between the ears and the lug allow considerable play in the joint. This permits a limited amount 75

of motion of the head to allow for inaccuracies in aligning the circuit breaker. Flexible conductors, such as braided strips 31, are connected across the joint 26 to insure good conduction. 5 As shown, the braids are held to the head by a ring 33 which is soldered, brazed, or otherwise fastened to the braid and to the conductor, and the braids are fastened to the arm by screws or bolts 32. There are obviously many possible 10 variations in the design details of this joint.

The head 11 comprises an insulated rod 35 bent at right angles just above the joint 26, on the end of which is located the contact member 34. The contact member consists of a plurality of 15 flexible fingers 52 fastened to the end of the conductor 35 by bolts or rivets 53 or otherwise fastened in a suitable manner. The fingers 52 are arranged around the conductor so that they enclose a tubular space into which slips the plug 20 type contact with which the member 34 co-operates. The fingers are corrugated or waved as shown in order to insure several points of contact on each finger with the co-operating contact member. To provide sufficient contact pressure, 25 garter type coil springs 54, 55 are provided encircling the group of fingers.

There are several known variations of this contact; for instance, in one known type the fingers are formed of a comparatively large 30 number of metal wires, each wire being bent into a number of curves or waves to increase the number of points of contact. Of course the locations of the plug and socket members can be reversed; that is, the fingers 52, forming the 35 socket 54, can be disposed within the stationary hollow bushing member 13 while the plug is disposed on the contact head 11. This is a less desirable arrangement, however, as maintenance is simplified by locating the more complicated 40 socket portion of the contact on the movable member 11, which can be more easily disconnected from the energized portions of the circuit for repair and replacement.

Referring to Figure 12, showing the contact 45 members in co-operation with each other. This drawing shows the hollow insulating bushing 97 in section, having a flange 110 having holes through which bolts 111 fasten the bushing to the panel 84. The bushing extends through a 50 hole 112 in the panel.

Within the bushing 97 is disposed the plug contact 99, which has a flange portion 113 fixed upon it. This flange bears upon the rear end wall 114 of the bushing. The shank 115 of the 55 plug extends through a hole in the end 114 of the bushing and is threaded to accommodate a nut 116, which is screwed up firmly against the bushing to hold the plug rigidly. The threaded end 101 of the contact plug is used as a terminal 60 for making connection with the bus bars or other parts of the circuit. The rod 35 is shown broken away ahead of the hinged joint 26. This drawing shows an additional protection against 65 accidental contact with live parts as furnished by an annular flanged member 117, preferably composed of insulating material. This flange is fastened to the movable contact head 11 and extends outwardly to cover the opening in the hollow bushing 97 when the contacts are in co- 70 operation. The flange is shown made in two halves which are clamped over the insulated rod 35 by means of bolts 118.

Referring again to Figures 4 and 5, the operation of connecting and disconnecting is accomplished by means of an attachment 36 that fits 75

tightly on the vertical portion of the head 11. Extending out on each side of the head are two projections or lugs 37, 38 in which are holes 39, 40 respectively. This attachment is engaged by a forked operating stick, which will be described in more detail later. This stick has projections which are inserted through the holes 39, 40, thereby allowing the connector to be controlled. 5

Around the bottom of the attachment 36 is a raised annular portion 41 over which a flexible 10 insulating sleeve 18 of rubber or the like is drawn and held in position to prevent accidental contact with the bare joint. The sleeve 18 and the braid 31 are broken away to show the details 15 of the joint.

The lower joint 42 between the contact arm 9 and the circuit breaker terminal 15 comprises a lug 43 on the terminal 15 which interleaves between two ears 44, 45 on the arm 9 and is joined to the ears by a bolt 46 which completes 20 the hinge. Excess play is allowed in this joint as well as in the upper joint to provide flexibility. Conduction is insured by flexible jumpers 47 for conducting current across the loose joint. These jumpers are riveted or soldered to the arm and 25 are secured to the terminal by the bolts 48. The insulating sleeve 19, shown in section, consists of a cylinder of insulating material having a closed upper end in which is a hole through which the arm 9 extends. This sleeve rests on 30 a ring or clamp 19' which is fastened on the arm 9. The sleeve extends around the joint down below the terminal on the circuit breaker bushing 15. The diameter of the sleeve is larger than that of the bushing to allow a limited angular motion of the arm. 35

Although the upper joint 26 is shown with a flexible sleeve 18 and the lower joint 42 is shown with a comparatively rigid insulating sleeve, either type of sleeve can be used on either upper 40 or lower joint.

In Figure 5 an additional slip joint 50 is shown in the arm which is not shown in Figure 4. In some cases it is desirable to provide for more flexibility than can be obtained by adding play 45 in the hinge joints. With this type of slip joint, it is possible to provide for several inches of vertical movement of the head by raising or lowering the arm. This type of joint also allows a rotary movement of the arm around the vertical axis of the terminal 15. It also allows the arm to be easily removed from the circuit breaker and another arm slipped on. The utility of this feature will be discussed in connection with a 50 later embodiment. 55

The joint 50 comprises a plug member 51, which is disposed above the lower hinged joint 42 and a socket member similar to the contact 34 on the head 11, consisting of a number of flexible fingers 52' fastened to the arm 9 by 60 rivets 53' or other suitable means. The fingers are bent into a number of waves or corrugations to insure several points of good contact with the plug member 51 and pressure is maintained by garter type springs 54', 55' around the socket 65 member over the points of contact. The sleeve 19' is made long enough to cover both the hinged joint 42 and the slip joint 50.

Referring back to Figures 1 to 3, control of the circuit breakers in the group of switching 70 units is transmitted from a remote operation position over control wires 60. These wires run through a conduit 61 which extends along the line of units through a continuous control cable housing 62 in front of the bus bar compartment 75

4. It is possible to omit the control cable conduit and simply lay the control cable in the cable compartment. The control wires for each unit terminate in a junction box 63 located in the control cable compartment of the switching unit.

From the junction box 63 the control cable 65 extends through the bottom of the compartment 62 into a control box 64 located on a hinged panel 66 directly in front of the jointed disconnect arms. The panel 66 is hinged at one side so that it may be swung away horizontally from in front of the circuit breaker. In or on the front of this control box are located the necessary relays, meters and junction boxes which are required for the operation of the circuit breaker. As this equipment is well known to those skilled in the art, the details of connections will not be described herein, but the control equipment is indicated as rectangles shown in broken lines in the control box 64. To establish connection with the operating mechanism 67 of the breaker, a short length of multi-conductor control cable 68 is shown leaving the operating mechanism 67 and terminating in a multiple circuit plug 69 which plugs into a co-operating socket 70 located in the floor of the control box 64.

The system of interlocks for insuring that the circuit breaker cannot be connected or disconnected from the bus and feeder circuit cables 5 unless it is in the open position is inherently very simple. An interlock rod 71 extends from the tripping latch in the circuit breaker operating mechanism to a pivoted arm 72 on the circuit breaker case. The other end of the arm 72 is connected to a rod 73 which is supported on a lug 74.

As the latch for tripping a circuit breaker is well known in the art, for the sake of simplicity the details of the tripping mechanism and the connection with the interlocking rod 71 are not included in the drawings. Suffice it to say that the common type of circuit breaker is closed by means of a motor or solenoid against a strong spring and is held closed by a latch. This latch can be opened either mechanically or by means of a solenoid which is controlled from the remote control position, thereby causing the spring to rapidly open the circuit breaker contacts. It is therefore obvious that the interlock rod 71 can easily be arranged in relation to the trip latch in such a manner that when the panel 66 is swung into the closed position as shown in Figure 1, the control box 64 engages the rod 73 and pushes it back into the position shown, thereby moving the interlocking rod 71 forward into the operating mechanism 67. When the rod is in this position, it does not engage the tripping latch. However, when the panel is opened, as illustrated in Figure 6, the rod 73 is pulled forward by the spring 75, drawing the interlock rod 71 back and causing it to actuate the tripping latch. In this manner the circuit breaker is tripped open when the front panel is opened. The control cable 68 is brought out of the operating mechanism 67 on the side away from the panel hinges so that as this length of cable is made appropriately short the control cable 68 must be disconnected by removing the plug 69 from its socket 70 in the control box, thereby preventing operation of the circuit breaker from a remote control station, before the front panel can be opened.

After the panel is open, the next step in removing the circuit breaker is to pull out the connectors 11, 12.

It is usually desirable to disconnect a circuit breaker from the bus first and from the feeder circuit last. This order of disconnecting is compelled by interlock spacing members 76. These members consist of sticks, preferably of insulating material, clamped on each of the longer connection arms 9 substantially at right angles to the arm. This member projects from the arm 9 to the head 12 of the rear contact member 10 and from the arm 9 to the control box 64. The length of each projection is made such that it prevents the front panel 66 from closing unless all contact plugs are pushed well into their respective contact bushings.

There are several obvious variations in the mechanical interlock 76, such as a bar extending out from the back of the control panel 64 which would interfere with the front connecting arms 9 unless they were in connected position, while a short spacing member between the front and rear arm could be fastened to the head 12 of the rear arm 10 instead of the front arm 9. Any variation of this device would obtain the result of spacing both front and rear arms within the enclosure so that with the front panel closed the contacts must necessarily all be in operating position.

It is obvious that a hinged or removable bar or other type of barrier can be substituted for the hinged panel to achieve the same ultimate result of a safety interlock. One of the essential features is a barrier which must be removed before the breaker is removed, the removal of the barrier being interlocked to cause the circuit breaker to trip open; the other feature is that the barrier must be closed before the circuit breaker can be closed, but the barrier is prevented from being closed unless the disconnect contacts are first closed.

This interlock 76 also prevents the rear contacts from being opened before the front contacts with the main bus are opened. After all contacts have been opened, the circuit breaker can be removed from the compartment.

The spacing members also perform another function, that of locking the arms in the connected position and preventing them from being forced out of contact in case of a heavy surge of current through the breaker due to a short circuit.

When replacing the circuit breaker, it is desirable that the connection with the bus be made after the feeder circuit connections are in place. The correct order of this operation is insured by the interlock 76 which requires the rear plug 12 to be closed into the contact before the front contact 11 can be pushed into place. The front panel 66 can be closed when all contacts are in the correct position, otherwise the interlock sticks 76 will interfere with the closing of the panel. With the closing of the panel, the interlock rod 73 is pushed back, thereby disengaging the tripping mechanism of the circuit breaker. The last operation is the plugging in of the control circuits, again establishing connection with the remote control station.

Access to the control box is obtained through a door 77 in the front panel 66. The door is opened by means of a handle 78. The front panel is opened by means of a second handle 79.

Access to the control cable compartment 62 is obtained through an opening in the front wall which is covered by a cover plate 80. The main bus compartment 4 is made accessible by remov-

ing a cover plate 81 in the top, or another cover 82 in the rear wall. A cover plate 83 covers an opening in the rear wall of the terminal compartment 6.

5 Figure 6 is a modification of Figure 1 showing a double bus design. In this drawing the contacts are shown in the open position. The method of opening the contacts is also illustrated. The operating stick 86 is shown engaged with the attachment 36 on one of the rear disconnect arms 10. The operating stick is also shown in plan view in Figure 7. It comprises a handle 87 and a pair of arms 88, 89 on the end of which are prongs 90, 91. The arms 88, 89 are spaced apart so that when engaged with a rear contact member as shown, one arm extends on each side of the corresponding front disconnect arm 9. The prongs are spaced apart a distance equal to the distance between the holes 39, 40 in the attachment 36. As the prongs fit reasonably close in the holes, contact head 12 can be aimed and controlled by means of the operating stick.

10 In Figure 6 a second set of bus bars 92 are disposed within a rear bus compartment 93. Access to this compartment is had through openings in the top and rear wall which are closed by covers 94, 95 respectively. The bus bars 92 are connected to the stationary contacts 13 by conductors 96. The bus bars 3 are connected by conductors 16 to an upper row of stationary contact members 99 above the contact members 13.

15 The circuit breaker as shown is prepared to connect the feeder cables 5 with the rear bus 92. When it is desired to connect to the front bus 3, the front row of hinged arms 9 are removed from the circuit breaker and longer ones 98 are attached as shown in dotted lines. This can be accomplished in several ways. The entire length of arm can be replaced by unbolting at the lower 20 joint 42, the head 11 can be removed at the upper joint 26, and a second head on an extension can be bolted in its place, or the arms can be provided with a slip joint 50 as shown in Figure 5, in which case the substitution is easily made by 25 slipping off one set of contact arms and replacing with a set of the longer ones.

20 Figures 8 and 9 show an elevation and plan of a third embodiment of the present invention. Figure 8 is a section taken along line 8-8 in Figure 9. In this case the bus bars 3 are omitted and insulated cables 102 are substituted. The bus compartment 103 extends along the row of switching units behind the stationary contact members forming a continuous bus housing, and the cables are laid in the housing. The bus housing in this case is shown to extend beyond the circuit breaker compartment 2 and is joined to the adjacent unit by bolting together the flanges 107 around the bus housing openings. In this arrangement no splicing is necessary, as can be seen in the plan view shown in Figure 9. The terminals 100 of the three contact members 120 of the center unit are connected to the respective terminals 104 on the contact members 121 in the adjacent unit on one side by three short insulated cables 102, while three other cables 106 connect the terminals 100 to those 105 on the members 122 in the adjacent unit on the other side. A new unit can be easily added to a group by placing it in line and connecting its contact terminals with the respective terminals of the adjacent unit by a set of short insulated cables. The bus, therefore, is composed of a series of jumper connections from 25 each switching unit to the next adjacent unit.

30 In Figures 8 and 9 the unit is shown with disconnect arms and contact members of another design. The details of this design are shown in Figures 10 and 11. This design is alternative to the design shown in Figures 4 and 5 and can be substituted in Figures 1, 2, 3 and 6. Likewise, the type described heretofore can be substituted in Figures 8 and 9.

35 Figure 10 is a side elevation of the alternative design showing the insulating bushing 123 of the stationary member 129 in section. Figure 11 is a front elevation of the assembly.

40 The disconnect arm 125 consists of a flat bar of conducting metal, the upper end being bent edgewise at substantially right angles to form 15 the contact blade. The contact portion 126 is adapted to co-operate with a stationary contact 127 of the conventional knife switch type, having a number of flexible fingers 128 to receive the blade 126. These fingers 128 are mounted on a 20 base 129 which bears on the bottom of the hollow portion of the insulating bushing 123. A stud 130, fastened to the base 129 of the switch contact, extends through a hole in the shank 131 of the bushing and is threaded at the end to receive a nut 132 which is drawn up to hold the contact 127 firmly in the bushing. A terminal member 108, adapted for receiving cables as shown in Figures 8 and 9, can be screwed on the threaded end of the stud 130 or the cable terminals can be 30 slipped directly over the stud and held by another nut in a well known manner.

45 A flange 133 is provided on the insulating bushing 123 for fastening the bushing on the panel 136 by means of bolts 134, the shank 131 of the bushing extending through a hole 135 in the panel 136.

50 As can be seen in Figure 11, the insulating bushing is oval shaped rather than circular. This allows somewhat closer spacing of the stationary 40 contact members, thereby requiring less angularity of the contact arms, as was explained in connection with Figure 3.

55 The arm 125 is insulated its entire length except on the contact blade 126 and on the lower 45 end 137 at the joint 138. On the circuit breaker stud 15 is mounted a double pronged lug 139. Between the prongs 140, 141 the end 137 of the arm 125 is inserted and a bolt 142 is inserted through registering holes in the prongs and the 50 arm. The arm thus hinges on the lug 139 and sufficient play is allowed in the joint to provide flexibility. A vertical misalignment between the movable 126 and stationary 127 contacts is permissible in this type of contact, due to the absence of mechanical obstruction to relative vertical movement between the two contact members.

60 Flexible conductors 143, 144 are fastened to the arm 137 by rivets 145 or the like, and are bolted to the lug 139 to insure good conduction around the joint. A flexible insulating sleeve 146 is shown in this embodiment although the rigid insulating sleeve shown in Figure 4 can be substituted.

65 At attachment 147 for operating the disconnect arm is clamped to the upper end of the arm. This attachment, which is constructed preferably of non-conducting material, is made in two parts 148, 149 which clamp together over the head of 70 the arm by bolts 150. Registering holes 154 are provided in the attachment 147 to accommodate an operating hook such as is used on conventional types of disconnect switches.

75 Flanges 151, 152, provided in the attachment, 75

are adapted to cover the opening in the front of the insulating bushing while the switches are closed.

While the drawings show a stationary structure fabricated from steel, it is quite evident that the stationary structure can be made of concrete, a combination of concrete and steel, or even an open framework of pipe or structural members, but still retaining the advantages of the method 5 of connecting the circuit breaker to the bus and feeder, the method of interlocking, and the arrangement of busses shown and described herein.

I do not intend to be limited to the details disclosed in these specifications and drawings. What I claim and wish to protect by Letters Patent is set forth in the following claims:

1. In a switching unit of the class described, 20 a set of bus bars, stationary contact members connected to said bus bars, a second set of bus bars, stationary contact members connected to said second set of bus bars, a portable circuit breaker, and means associated with said circuit breaker for making connection selectively with either set of bus bars, said means comprising two interchangeable sets of hinged contact arms co-operable respectively with said stationary contact members of each set of bus bars, said contact arms having slip joints for interchangeably connecting them to said circuit breaker.

2. In a switching station of the class described, a portable circuit breaker having a terminal post, a stationary contact member, means attached to said circuit breaker comprising an assembly of insulated conducting links joined together by a plurality of independently flexible joints for connecting said terminal post to said stationary contact, insulating sleeves covering said joints, and operating lugs projecting from 40 opposite sides of one of said links, whereby said conducting links can be guided into connection with said stationary contact member.

3. In an electric system, a plurality of metal clad switchgear units, each unit having flexibly 45 jointed disconnecting contacts and a metal bus compartment, said compartment having apertures in a wall thereof, and openings at opposite ends thereof, and insulating shields supporting fixed disconnecting contacts adapted to co-50 operate with said flexibly jointed disconnecting contacts, said shields being mounted in and extending through said apertures, the respective switchgear units being in alignment, the end openings of the bus compartments of adjacent 55 units being in communication, and buses comprising short lengths of insulated cables extending from the fixed disconnecting contacts in each compartment through said openings to respective fixed disconnecting contacts in the adjacent 60 compartment.

4. In a switching structure of the class described, the combination of a stationary conductor, a portable circuit breaker, and means mounted on said circuit breaker for connecting 65 the circuit breaker to the stationary conductor, said means comprising an insulated conducting blade hinged at the circuit breaker connection, the free end of said blade being bent substantially at right angles, contact means at the end of 70 said blade, and a stationary contact adapted to co-operate with said contact means, said stationary contact being mounted within a hollow insulating bushing and connected to said stationary conductor.

5. In combination, a horizontally disposed hollow insulating shield, a stationary switch contact disposed therein, a terminal post movable with respect to said stationary contact and normally disposed below said contact, a switch arm supported on said post by a flexible joint, said arm comprising an insulated blade, the free end of said blade having a substantially right-angle bend, and a contact portion at the end of said blade co-operable with said stationary contact, whereby movement of said arm on said joint provides for the insertion of said free end of the blade into said hollow shield and the contacting of said co-operable contacts.

6. In combination, a plug contact member, a 15 socket contact member, a horizontally disposed hollow insulating supporting shield for one of said members, said last mentioned contact member being disposed horizontally within said hollow shield, an elongated insulated contact head 20 for supporting the other of said members, an insulated conducting arm, a flexible joint connecting said head to one end of said arm, a terminal post, a second flexible joint connecting the other end of said arm to said terminal post, whereby 25 motion of said arm on the last mentioned joint provides for bringing said contact head up in approximate alignment with said hollow shield, and motion of said head on the first said joint provides for aligning the contact member supported 30 thereon with said horizontally disposed contact member.

7. In combination, a row of front terminal lugs, a row of rear terminal lugs substantially in alignment therewith, a conducting arm hinged to each 35 of said lugs, a movable contact on each of said arms, corresponding stationary contacts co-operable with said movable contacts respectively, insulating supports for said stationary contacts, a movable barrier normally disposed in front of the 40 front row of arms, and spacing members attached to certain of said arms for spanning from the arms in the front row to said barrier and from the last mentioned arms to the arms in the rear row when contacts are in co-operation and said barrier is in 45 normal position.

8. In combination, a stationary contact, an insulating support therefor, a terminal post normally disposed below said contact and movable therefrom, a conducting arm movably jointed 50 to said terminal post, an elongated contact member movably jointed to said arm, the movement of said member with respect to said arm being independent of the movement of said arm with respect to said post, said contact member being co-operable with said stationary contact, operating lugs projecting on opposite sides of said contact member, said lugs being engageable by a double pronged operating stick for guiding said member into contact with said stationary 55 contact.

9. In combination, a circuit breaker, a front terminal post, a rear terminal post, a switch arm movably jointed to each of said terminal posts, stationary contacts mounted on insulating supports, said contacts being co-operable respectively with said switch arms, operating lugs projecting from opposite sides of each of said switch arms, and a double pronged operating stick adapted to engage said lugs, whereby to engage the switch 65 arm on said rear terminal post, said operating stick straddles the switch arm on said front terminal post.

10. In combination, a stationary contact mounted within a horizontally disposed hollow 75

insulating bushing, a movable contact co-operable with said stationary contact, said movable contact being connected to one end of a contact head comprising an elongated conducting member 5 having an insulating covering, said head being adapted for insertion into said insulating bushing for establishing contact between said movable and fixed contacts, a rigid insulated conducting arm, said contact head being supported at one 10 end of said arm by a movable joint, an insulating covering for said joint, a terminal lug, an insulating support therefor, said lug being connected to the other end of said arm by a second movable joint, and an insulating covering for said 15 second joint.

11. In combination, a circuit breaker having a row of front terminals and a row of rear terminals, a pair of electric circuits adapted to be interconnected by said circuit breaker, a first row 20 of stationary contacts connected to one of said circuits, insulating supports therefor disposed above said circuit breaker, a second row of stationary contacts connected to the other of said circuits, insulating supports therefor, said second 25 row of contacts being disposed below said first row of contacts, a two-jointed connecting arm movably jointed to each of said front terminals, contact heads bearing contact members co-operable respectively with said first row of stationary 30 contacts, one of said heads being movably jointed to each of said connecting arms, and a two-jointed connecting arm movably jointed to each of said rear terminals, contact heads bearing contact members co-operable respectively with said second 35 row of stationary contacts, one of said heads being movably jointed to each of the last mentioned arms.

12. In combination, a stationary contact mounted within a horizontally disposed hollow 40 insulating bushing, a terminal lug, a supporting bushing therefor disposed below said hollow bushing, an upwardly extending insulated conducting arm connected to said lug by a hinged joint, a horizontally disposed contact head connected to 45 the end of said arm by a second hinged joint, insulating sleeves covering each of said hinged joints, a contact member disposed on said contact head, said member being co-operable with said stationary contact, and means for guiding said 50 head and contact member into said hollow bushing and into co-operation with said stationary contact.

13. In combination, a stationary contact, an insulated support therefor, a terminal post movable 55 with respect to said stationary contact, a conducting arm hinged to said post, a contact head hinged to the free end of said arm, a contact member carried on said contact head, said member being co-operable with said stationary contact, and additional means for compensating for a limited misalignment of said terminal post with 60 respect to said stationary contact.

14. A switching station of the class described, comprising in combination, a set of bus bars, an 65 electric circuit adapted for connection thereto, stationary contact members mounted within horizontally disposed hollow insulating bushings and connected to said bus bars and said circuit respectively, a portable circuit breaker having terminal posts, a rigid insulated conducting arm hinged to each of said terminal posts, an insulated 70 contact head hinged to each of said arms, said hinged connections permitting movement of said contact heads with respect to said arms, inde-

pendent of the movement of said arms with respect to said posts, a contact member carried on each of said contact heads, and means for manually guiding said contact heads into said bushings and for establishing connection with 5 said stationary contact members.

15. In a switching station of the class described, a portable circuit breaker, a terminal post on said breaker, a stationary contact member, and means attached to said breaker for selectively connecting said terminal post to said stationary contact, said means comprising a plurality of conducting links serially joined together and to said post by flexible joints, said joints being operable independent of each other. 15

16. In combination, a stationary contact member mounted within a horizontally disposed hollow insulating shield, a movable contact head having a contact member co-operable with said stationary contact member, a terminal post, 20 means for connecting said post to said contact head, said means providing a rigid supporting arm for said contact head, said means including conducting means and including also insulating means surrounding the conducting means, a flexible joint for connecting one end of said arm to said head, and a second flexible joint for connecting the other end of said arm to said terminal post, said flexible joints permitting movement of 25 said head with respect to said arm independent of movement of said arm with respect to said post.

17. In combination, a portable circuit breaker having a terminal, a stationary contact member mounted within a horizontally disposed hollow insulating shield, a contact head having a contact 30 member co-operable with said stationary contact member, and means connecting said circuit breaker terminal and said contact head, said means providing a rigid arm supported on said circuit breaker on a flexible joint and including also 40 insulating means surrounding the arm, said head being jointed to the free end of said arm, said flexible joints permitting movement of said head with respect to said arm independent of movement of said arm with respect to said circuit 45 breaker.

18. A switching station of the class described, comprising in combination a set of bus bars, an electric circuit adapted for connection thereto, stationary contact members mounted within horizontally disposed hollow insulating bushings and connected to said bus bars and to said circuit respectively, a portable circuit breaker for connecting said bus bars and said circuit, said breaker having a terminal corresponding to each of said 55 stationary contact members respectively, a movable contact member co-operable with each of said stationary contact members respectively, each of said movable contact members being supported on an insulated head, means for connecting each of said movable contact members to said circuit breaker terminals respectively, said means providing supporting arms for said contact heads and including also insulating means surrounding the respective arms, each of said heads being 60 mounted on one end of one of said arms respectively with a limited amount of movement with respect thereto, and means for supporting the other end of each of said arms on said circuit breaker, said supporting means permitting movement of 65 said arms relative to said circuit breaker independent of the motion of said contact heads relative to said arms.

ALLEN M. ROSSMAN.
